UNITED STATES PATENT OFFICE.

WILLIAM M. DUNN, OF SHELBYVILLE, INDIANA, ASSIGNOR OF ONE-HALF TO EMANUEL HENDRICKS, OF SHELBYVILLE, INDIANA.

DAMPER-OPERATING DEVICE.

1,274,251.

Specification of Letters Patent.

Patented July 30, 1918.

Application filed November 25, 1916. Serial No. 133,463.

To all whom it may concern:

Be it known that I, WILLIAM M. DUNN, a citizen of the United States, residing at Shelbyville, in the county of Shelby and State of Indiana, have invented new and useful Improvements in Damper-Operating Devices, of which the following is a specification.

This invention relates to a damper operating device which may be employed to operate the dampers in flues associated with boilers for generating steam and by means of which the current of air passing through the fire box in the boilers for promoting combustion may be controlled.

The primary object of the invention is the provision of a damper operating device of this character which when applied to a boiler for generating steam may be advantageously used to automatically maintain the steam within the steam chamber of the boiler at a predetermined pressure.

Another object of the invention is to provide a damper operating device of the class described which is so constructed that when connected with a boiler for generating steam it is operable under the influence of the steam in the steam chamber of the boiler to automatically move the damper in the flue associated with the boiler to a position to decrease the current of air passing through said flue and the fire box under the boiler upon the steam in the steam chamber reaching a predetermined pressure and upon a reduction of this pressure due to the decrease in the current of air passing through the fire box and flue to again move the damper in said flue to a position in which the current of air passing therethrough is increased thus maintaining the steam in the steam chamber of the boiler at a predetermined pressure and controlling the amount of fuel consumed for this purpose.

Another object of the invention is to provide a damper operating device of the class described wherein the damper arranged in the flue of a steam generating device and controlling the current of air through the fire box thereof and said flue is normally held in an inactive position against the influence of a weight connected therewith by a weighted piston having connection with said damper and arranged in a steam cylinder connected with the steam chamber of the

steam generating device in such a manner that when the steam in said chamber reaches a predetermined pressure the piston in said cylinder will be raised against the influence of the weight thereon and allow the weight connected with the damper to move the same to an active position.

With these and other objects in view, the invention resides in the novel combination and arrangement of parts, which will be hereinafter described and particularly pointed out in the claims.

The preferred embodiment of the invention has been illustrated in the accompanying drawing, although no restriction is necessarily made to the precise details of construction therein shown, as changes, alterations, and modifications, within the scope of the claims may be resorted to when desired.

The figure in the drawing is a view in elevation partly in section of a damper operating device constructed in accordance with the invention and showing the same applied to a steam generating device, the damper in the flue associated therewith being shown in its normal or open position.

Referring now to the drawing in detail, the numeral 1 designates a steam generating device which in this instance has been shown as a tubular boiler having associated therewith the usual flue 2 in which is arranged a damper 3 for controlling the passage of a current of air through the fire box of said boiler and flue, said damper having connected therewith an operating arm 4 arranged exteriorly of the flue 2 and having adjustably mounted thereon a weight 5 normally exerting an influence upon the arm 4 to move the damper 3 within the flue 2 to an inactive position or to a position in which a current of air will be prevented from passing through the fire box of the boiler and through said flue.

A steam cylinder 6 which is arranged adjacent the boiler 1 has mounted to slide therein a steam operated piston 7, the stem 8 of which passes through one end of the cylinder and through guides 9 mounted thereon and has connection with the arm 4 on the damper 3 through the medium of a flexible member 10 terminally connected with the stem 8 and trained over pulleys 11 connected with a suitable support 12 which

in this instance has been shown as the ceiling of the building in which the boiler is located.

The weight of the piston 7 is equal to the 5 weight 5 on the arm 4, so that as the piston 7 is moved upwardly in the cylinder 6, the arm 4 is correspondingly lowered and as the piston 7 again moves downwardly in the cylinder 6, the arm 4 is correspondingly 10 raised thus operating the damper 3 and controlling the passage of air through the fire box and flue 2 of the boiler 1.

An exhaust pipe 13 has connection with the cylinder 6 below the piston 7 therein and 15 is provided with a valve 14 for closing the passage therein, said valve being normally held in an open position by a weight 15 adjustably mounted on an arm 16 pivotally connected with the pipe 13 and having connection with the stem on the valve 14. The 20 valve 14 has formed therein a bleed port through which steam within the cylinder 6 may pass when the valve 14 is in closed position.

25 A steam supply pipe 17 has one end thereof connected with the exhaust pipe 13 between the lower end of the cylinder 6 and the valve 14 and has its other end connected with the steam chamber in the boiler 1 and 30 provided with a spring pressed valve 18 for normally closing the passage through the steam supply pipe 17 but operable by the steam within the steam chamber in the boiler 1 upon reaching a predetermined pressure 35 sure to open to permit said steam to pass through the supply pipe 17 and into the cylinder 6, it, of course, being understood that the pressure of the steam in the pipe 17 is sufficient to counter-balance the weight 15 40 and close the valve 14.

The steam supply pipe 17 is also in communication with the interior of the cylinder 6 above the piston 7 through the medium of a branch pipe 19 terminally connected with 45 the cylinder and steam supply pipe 17 and having arranged therein a check valve 20 serving to prevent the equalization of steam pressure upon opposite sides of the piston head 7 within the cylinder 6 when steam is 50 admitted to the lower portion of the cylinder through the supply pipe 17.

A weight 21 is connected with the stem 8 of the piston 7 and mounted to slide on the guides 9 upon one end of the cylinder, said 55 weight 21 normally serving to counter balance the weight 5 on the arm 4 and hold the piston 7 in lowered position in the cylinder 6 so that the damper 3 is normally held in the flue 2 in an inactive position against the 60 influence of the weight 5.

A cut off valve 22 is arranged in the steam supply pipe 17 between the valve 18 and the steam chamber in the boiler 1.

When the improved damper operating device has been connected with a steam gen-

erating device as shown in the figure in the drawing, it will be seen that the weight 21 normally holds the piston 7 in lowered position in the cylinder 6 so that the damper 3 in the flue 2 is held in an inactive position 70 until the steam in the steam chamber of the steam generating device has reached a predetermined pressure at which time the valve 18 in the steam supply pipe 17 will be opened by the steam in the steam chamber and steam 75 admitted to the cylinder 6 beneath the piston 7 said steam counter-balancing the weight 15 and closing the valve 14 in the steam exhaust pipe 13 and also operating the check valve 20 to close the passage in the 80 branch pipe 19.

As the piston 7 moves upwardly in the cylinder 6 under the influence of the steam admitted thereto through the pipe 17, the arm 4 is correspondingly lowered by the upward movement of the piston and the weight 5 on the arm 4 so that the damper 3 in the flue 2 is moved to a position to decrease the current of air passing through the fire box 90 of the steam generating device and the flue 2 thus controlling combustion within the fire box and causing a correspondingly decrease of steam pressure in the steam chamber 95 of the steam generating device.

As the steam pressure in the steam chamber 100 of the steam generating device decreases below a predetermined degree the valve 18 closes the passage through the steam supply pipe 17 so that the steam which is confined in the lower portion of the cylinder 6 gradually escapes through the bleed port in the valve 14 until the steam pressure in the bottom of the cylinder is such that the weight 15 may move the valve 14 to an open position 105 at which time the weight 21 on the stem of the piston will gradually lower the same in the cylinder 6 as the steam escapes therefrom and raise the arm 4 until the damper and piston have reached their normal positions.

110 From the foregoing description, taken in connection with the accompanying drawing, it is at once apparent that a damper controlling device has been provided which when applied to a steam generating device of the class described will regulate the quantity of steam generated thereby and control the consumption of fuel for this purpose, said device being simple in construction, therefore inexpensive of manufacture, yet 115 highly efficient in use.

Having thus described the invention, what is claimed as new, is:

1. In a damper operating device, in combination, a steam generating device having a flue associated therewith, a damper mounted to turn in said flue to control the draft of air therethrough, an operating arm on said damper arranged exteriorly of said flue, a steam cylinder, a piston mounted to slide in 130

- said steam cylinder and having connection with said operating arm, a weight adjustably mounted on said operating arm to serve as a balance weight for said piston, a weight on 5 said piston for normally holding the same in lowered position within said steam cylinder, a steam supply pipe having connection with the steam generating device and the interior of the steam cylinder below said piston, 10 ton, means for controlling the admission of steam from said steam generating device to said cylinder to raise the piston thereon against the influence of the weight thereon, a steam exhaust pipe having communication 15 with the interior of said cylinder and the steam supply pipe, and a normally open weight controlled valve in said steam exhaust pipe to be moved to a closed position by steam admitted to said cylinder, said valve 20 having a bleed port therein.
2. In a damper operating device, in combination, a steam generating device having a flue associated therewith, a damper mounted to turn in said flue to control the passage of 25 the air therethrough, an operating arm on said damper arranged exteriorly of said flue, a weight adjustably mounted on said operating arm, a steam cylinder, a piston mounted to slide in said steam cylinder and having 30 connection with said operating arm to serve as a balance weight for the weight on the operating arm, a counter-balance weight on said piston normally holding the same in lowered position within said cylinder, a 35 steam supply pipe having connection with the steam generating device and the interior of the steam cylinder below said piston, means for controlling the passage of steam from said steam generating device through 40 the supply pipe to raise said piston within said cylinder, a steam exhaust pipe having connection with the interior of said cylinder
- below said piston and the steam supply pipe, means in said exhaust pipe for controlling the escape of steam from said supply pipe 45 and the interior of said cylinder, a branch pipe having connection with the interior of said cylinder above said piston and with the steam supply pipe, and a steam operated check valve within said branch pipe controlling the passage of steam therethrough.
3. In a damper operating device, in combination, a steam generating device having a flue associated therewith, a damper mounted to turn in said flue to control the passage of 50 air therethrough, an operating arm on said damper arranged exteriorly of said flue, a steam cylinder, a piston mounted to slide in said cylinder and having flexible connection with said operating arm, a weight on said piston normally holding the same in lowered position within said cylinder, a steam supply pipe having connection with the steam generating device and the interior of the steam cylinder below said piston, automatic pressure operated means for controlling the passage of steam from said steam generating device through the supply pipe to raise said piston within said cylinder, a steam exhaust pipe having connection with the interior of 55 said cylinder at the bottom thereof, a normally open weight controlled valve in said steam exhaust pipe to be moved to a closed position by steam admitted to said cylinder, said valve having a bleed port therein, a 60 branch pipe having connection with said steam supply pipe and communicating with the interior of said cylinder above said piston, and a steam operated check valve within said branch pipe controlling the passage 65 of steam therethrough.

In testimony whereof I affix my signature.

WILLIAM M. DUNN.
